UNITED STATES PATENT OFFICE.

FREDERICK D. GATCHELL, OF NEW YORK, N. Y.

GREASE CAN OR CARTRIDGE.

Original application filed June 16, 1926, Serial No. 116,433. Divided and this application filed September 21, 1926. Serial No. 136,815.

The invention relates more particularly to grease cartons or containers mainly intended for service with portable grease dispensing apparatus of the type in which the 5 ton is applied not unlike a cartridge and is discharged by a plunger element; and this application is a division of application, Ser. No. 116,433, filed June 16, 1926.

The object of the invention is to provide 10 a simple and comparatively inexpensive original package of lubricant which will insure quality and quantity of product and which will cooperate with the dispensing apparatus in a highly efficient manner.

15 The nature of the invention consists in packing the grease or lubricant in a cylindrical container or can having a solid or intact bottom closure and a friction seal or movable top closure adapted and arranged 20 to be dislodged by the plunger element of a grease dispensing apparatus and to operate in advance thereof in such way as to insure the complete discharge of the contents of the package through the bottom of the container 25 following the rupture of the bottom closure by a mechanically operated piercing element.

One embodiment of the invention is illustrated in the annexed drawing, wherein—

30 Figure 1 is a vertical sectional view of the can, including end closures.

Fig. 2 is an end view of the friction seal.

Fig. 3 shows the inverted cup packing or stripping gasket.

35 According to my invention a cylindrical sheet metal or other can body 5 is formed or equipped with an intact or solid metal bottom closure 6, and with an inside flange or rim seat 7 forming an element of a friction seal or movable closure. The rim seat 7 may be externally dished or guttered, as at 40 8, to promote the inherent resiliency thereof, and its inner edge may have a depending skirt 9. The merit of the skirt is that it 45 provides increased area of friction surface for the movable closure. The latter is a sheet metal disk 10 adapted and arranged for sliding movement in the can. The disk 10 is stamped or otherwise formed with an

50 upstanding boss or crown portion 11 designed to frictionally engage the flange or rim seat 7. The major diameter of the disk is substantially the same as the inside diameter of the can. At any rate it is desirable 55 to establish a snug fit between the margin

12 and the can. The presence of the bead 13 is advantageous in that it promotes sliding action.

Intermediate the movable end closure or disk 10 and the grease or other filling is a 60 packing disk 14. The latter may well be constructed of material such as leather, tough paper or the like. Its office is to prevent grease from bypassing the disk 10, when the can is being discharged and to 65 thoroughly strip the can. These results are accomplished by providing a flexible disk initially of greater diameter than the inside diameter of the can and imparting to it the cup shape shown. The cup disk is applied 70 in inverted state so that in response to pressure upon the disk its skirt or margin 15 will frictionally engage the can body and thoroughly scrape or strip the same.

75 In practice, following the rupture of the bottom closure by a mechanically operated die or piercing element, for example in the manner disclosed in the application hereinbefore referred to, the disk 10, will be impinged upon by the plunger element of the 80 apparatus and under exerted force will move downwardly and so move the packing and stripping disk 14, the advanced rim of which will tightly bind against the inner wall of the can thoroughly scraping the 85 same and preventing any grease from bypassing the disk 10.

Having described my invention, I claim—

1. A grease container of the character stated, comprising a can having end closures 90 whereof one is solid and designed to be ruptured and whereof the other is slidable under exerted pressure and is provided with a boss, and an annular flange on the can in frictional sealing relation with the boss. 95

2. A grease container of the character stated, comprising a can having end closures whereof one is solid and designed to be ruptured and whereof the other is slidable under exerted pressure and is provided with 100 an outwardly directed boss, a rim seat to accommodate the boss and forming therewith a friction seal, and a stripper intermediate the grease and the slidable closure.

3. A grease container of the character stated, comprising a can having end closures whereof one is solid and designed to be ruptured and whereof the other is slidable under exerted pressure, said slidable closure 105 consisting of a disk having an endwise di- 110

rected boss, and a collar within the can body to cooperate with the boss in friction seal relation.

4. A grease container of the character stated, comprising a can having end closures whereof one is solid and designed to be ruptured and whereof the other is slidably under exerted pressure, said slidable closure

consisting of a disk having an endwise directed boss, a collar within the can body to cooperate with the boss in friction seal relation, and an inherently resilient rim lock adapted and arranged to cooperate with the boss to establish a friction seal. 10

In testimony whereof I affix my signature.

FREDERICK D. GATCHELL.
